(57) **CLAIM**

I claim the ornamental design for a wallet, as shown and
described.

DESCRIPTION

A portion of the disclosure of this patent document contains
material to which a claim for copyright is made. The
copyright owner has no objection to the reproduction of the
patent document or the patent disclosure, as it appears in the
U.S. Patent Office records, but reserves all other copyright
rights whatsoever.

FIG. 1 is a front view of a wallet, showing my new design,
shown in a closed position;

FIG. 2 is a front, right side perspective view thereof, shown
in a closed position;

FIG. 3 is a rear view thereof, shown in a closed position;

FIG. 4 is a rear, right side perspective view thereof, shown
in a closed position;

FIG. 5 is a top plan view thereof, shown in a closed position;

FIG. 6 is a left side elevational view thereof, shown in a
closed position;

FIG. 7 is a front view thereof, shown in an open position;

FIG. 8 is a rear view thereof, shown in an open position;

FIG. 9 is a front view of a second embodiment of a wallet,
shown in a closed position, the rear, top, and left side views
being identical to the first embodiment;

FIG. 10 is a front elevational view thereof, shown in an open
position;

FIG. 11 is a rear elevational view thereof, shown in an open
position;

FIG. 12 is a front view of a third embodiment of a wallet,
shown in the closed position;

FIG. 13 is a rear view thereof, shown in a closed position;

FIG. 14 is a rear, right side perspective view thereof, shown
in a closed position;

FIG. 15 is a top plan view thereof, shown in a closed
position;

FIG. 16 is a left side elevational view thereof, shown in a
closed position;
